UNITED STATES PATENT OFFICE.

WILLIAM S. RICHARDSON, OF BOSTON, MASSACHUSETTS.

DESIGN FOR A SOCKET MEMBER FOR DETACHABLE FASTENERS.

SPECIFICATION forming part of Design No. 27,538, dated August 17, 1897.

Application filed June 23, 1897. Serial No. 642,000. Term of patent 14 years.

To all whom it may concern:

Be it known that I, WILLIAM S. RICHARDSON, a citizen of the United States, residing at Boston, in the county of Suffolk and State of Massachusetts, have invented and produced a new and original Design for the Socket Members of Detachable Fasteners, of which the following is a specification, reference being had to the accompanying drawings, forming a part thereof.

In the drawings, Figure 1 is a view in perspective of the fastener. Fig. 2 is a view in perspective of the same inverted. Fig. 3 is a view in section.

15   a is a flange circular in shape and which

may or may not have perforations or holes in it. From it extends the conical wall a' , from the end of which extends inward the cylindrical wall a^2 , which is shaped to form a narrow rim a^3 , surrounding the hole a^4 .

20

Having described my invention, what I claim as new, and desire to secure by Letters Patent of the United States, is—

The design for a socket member of a separable fastener herein shown and described. 25

WILLIAM S. RICHARDSON.
